Primary Examiner — Ian Simmons*Assistant Examiner* — Rhea Shields(74) *Attorney, Agent, or Firm* — King & Spalding LLP(57) **CLAIM**

The ornamental design for a USB receptacle device, as shown and described.

DESCRIPTION

FIG. 1 is a side perspective view of a USB receptacle device, showing our new design;

FIG. 2 is a front elevation view thereof;

FIG. 3 is a back elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a side perspective view of another new ornamental design for a USB receptacle device;

FIG. 9 is a front elevation view of the USB receptacle device of FIG. 8;

FIG. 10 is a back elevation view of the USB receptacle device of FIG. 8;

FIG. 11 is a left-side elevation view of the USB receptacle device of FIG. 8;

FIG. 12 is a right-side elevation view of the USB receptacle device of FIG. 8;

FIG. 13 is a top plan view of the USB receptacle device of FIG. 8; and,

FIG. 14 is a bottom plan view of the USB receptacle device of FIG. 8.

The broken lines shown represent unclaimed subject matter and form no part of the claimed design.
